(57) **CLAIM**

The ornamental design for a tissue transfer apparatus, as shown and described.

DESCRIPTION

FIG. 1 is an environmental front perspective view of a tissue transfer apparatus;

FIG. 2 is a front perspective view thereof;

FIG. 3 is a rear perspective thereof;

FIG. 4 is an environmental left side elevation view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a right side elevation view thereof; and,

FIG. 10 is a left side elevation view thereof.

All features illustrated in phantom line are expressly disclaimed and form no part of the claimed design.
